EX

D7-372

OR D 7,723

DESIGN.

W. HASLAM.

Spice-Mills.

Patented Sept. 1, 1874.

No. 7,723.

UNITED STATES PATENT OFFICE.

WILLIAM HASLAM, OF PHILADELPHIA, PENNSYLVANIA, ASSIGNOR TO
AUGUST NETTINGER, JR., OF SAME PLACE.

DESIGN FOR SPICE-MILL.

Specification forming part of Design No. 7,728, dated September 1, 1874; application filed July 21, 1874.
[Term of Patent 7 years.]

To all whom it may concern:

Be it known that I, WILLIAM HASLAM, of the city of Philadelphia and State of Pennsylvania, have originated or invented a new Design for a Spice-Mill; and that the following is a full and exact description thereof, reference being had to the accompanying drawing, and to the letters of reference marked thereon.

Figure 1. A is the fly-wheel, with rim of octagon form, with three arms extending out from the hub, and connecting with rim at six different points of half-circle shape.

Fig. 2. B is the hopper, of octagon form on top, with half-round molding projecting around the top edge; side of hopper slight ogee form.

Fig. 3. C is the grinding-chamber, with a flat surface, with a center of conical form sufficient to admit the shaft through, the outside edges of chamber-plates of half-circle form; also, a half-round ear in the center, at top of chamber-plate; also, chamber-support pieces

in center, at bottom, of a hollow and square form.

Fig. 4. D is the stand, with four legs, having at the extreme ends rounding ears; legs with a bold curve, connecting at corners of top of stand; corners of top of stand of a double round form; sides of stand or base extending down one-fourth, with two half-round forms, connecting with the curves at the corners of top of stand.

Fig. 5. E is the drawer, form of same flat surface, with an apron projecting from the top part of drawer; front of a double ogee form, and knob in center on front.

What I claim as my invention, and desire to secure by Letters Patent, is—

The design for a spice-mill, herein set forth.

WM. HASLAM.
